FLOWER VASE OR SIMILAR ARTICLE

Arthur L. Harshman, Dunkirk, Ind., assignor to Indiana Glass Company, Dunkirk, Ind., a corporation of Indiana

Filed Jan. 28, 1964, Ser. No. 78,389

Term of patent 14 years

(Cl. D29—28)

FIG. 1 is a side elevational view of a flower vase or similar article showing my new design;

FIG. 2 is a top plan view;

FIG. 3 is a horizontal sectional view taken through the stem portion of the flower vase or similar article along the line 3—3 of FIG. 1; and

FIG. 4 is a fragmentary horizontal sectional view taken through a segment of the bowl portion of the flower vase or similar article.

I claim:

The ornamental design for a flower vase or similar article, substantially as shown.
